UNITED STATES PATENT OFFICE.

JOHN McMARTIN, OF JANESVILLE, WISCONSIN.

BUCKLE GAG-RUNNER.

Specification forming part of Letters Patent No. **40,636**, dated November 17, 1863.

To all whom it may concern:

Be it known that I, J. McMARTIN, of the city of Janesville, county of Rock, and State of Wisconsin, have invented a new and Improved Mode of Constructing Buckle Gag-Runners; and I do hereby declare that the following is a full, clear, and exact description of the construction and operation of the same, reference being had to the accompanying drawings, making a part of this specification, like characters referring to like parts in each figure.

The nature of my invention consists in combining a buckle with a gag-runner, in the manner and for the purposes hereinafter set forth.

Figure 1 is a front view of the swivel, showing its connection with the crown-piece of the bridle. Fig. 2 is a flank view of the same.

D, Fig. 1, represents the point at which the bridle-front is attached. E is a rosette. G is

the blind-strap. C is the buckle-bar. B is the buckle-tongue. A is the buckle gag-runner as a whole. F is the throat-latch strap, and to this strap is attached the buckle gag-runner, and by means of its combination with the buckle it may be raised or lowered until it is adjusted to the satisfaction of the operator. By the old method of construction the buckle gag-runner had, of necessity, to remain stationary, whereas, by this mode, as herein described, it may be moved up or down near, or quite, six inches, thus securing the desideratum long sought after.

What I claim as new, and for which I ask Letters Patent, is—

The combination of the gag-runner and buckle B, as arranged and described

JOHN McMARTIN.
